OR D 17,244

Substitute for Missing OR

UNITED STATES PATENT OFFICE.

CHARLES B. SMITH, OF FITCHBURG, MASSACHUSETTS.

DESIGN FOR A FABRIC.

SPECIFICATION forming part of Design No. 17,244, dated April 5, 1887.

Application filed January 5, 1887. Serial No. 223,503. Term of patent 3½ years.

To all whom it may concern:

Be it known that I, CHARLES B. SMITH, of Fitchburg, in the county of Worcester and State of Massachusetts, have invented and produced a new and original Design for Fabrics, of which the following is a full, clear, and exact specification.

The nature of my design is fully represented in the accompanying photograph, to which reference is made.

The design consists, principally, of herringbone stripes *a* and solid stripes *b*, alternating the stripes *a*. The stripes *b* show diagonal lines or ribs *c* approaching the center of the stripe from its opposite edges. The stripes *a* are made up of transverse stripes *a'*, of one color, and the transverse stripes *a''*, of another color. These stripes *a' a''* are V-shaped, and

the stripes *a''* show two colors, one member of the V being light, the other dark, so that the stripes *a* present to the eye the appearance of two distinct and variegated stripes, as shown in the accompanying photograph.

I claim--

The design for fabrics herein shown and described, the same consisting of the ground stripes *b*, showing diagonal stripes *c*, and intermediate stripes, *a*, showing V-shaped diagonal stripes *a'* and also V-shaped transverse stripes *a''*, the said V-shaped stripes *a''* showing distinct diagonal members meeting in the center of the stripe *a*.

CHARLES B. SMITH.
